UNITED STATES PATENT OFFICE.

ELMER R. CORWIN, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONY.

1,173,773.

Specification of Letters Patent. Patented Feb. 29, 1916.

Application filed April 5, 1913. Serial No. 759,020.

To all whom it may concern:

Be it known, that I, ELMER R. CORWIN, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephone exchange systems and has a number of objects and advantages in view.

My invention finds an important embodiment in so-called automatic telephone exchange systems where calling subscribers are enabled to effect connection between their lines and desired lines, though the invention has many characteristics which are not to be limited to systems of this class as will be apparent from a full description of one embodiment of the invention that is to be given.

My invention has for one of its objects the provision of link connectors and electro-magnetic switches for connecting the link connectors with lines and also with other link connectors which are controlled by the talking sides of the link connectors independently of third conductors.

My invention has for another of its objects the provision of electro-magnetic means operating normally to divide the link connectors into sections whereby traveling members which are used to extend telephone lines and link connectors may remain in contact with the waiting contacts they were caused to engage in establishing connections when the connected parties are through conversation whereby stepping up and releasing mechanism individual to the link circuit may be dispensed with.

My invention has for another of its objects the provision of master switching mechanism common to the link connectors or telephone conductor sections of a group, additional link connectors or telephone conductor sections, switching devices for connecting the latter link connectors or telephone conductor sections with the former and setting up switching mechanism for bringing these switching devices within the control of the circuits with which the master switching mechanism is associated whereby desired extensions may be applied

to calling lines without the aid of stepping up devices and releasing mechanism for restoring the equipment to normal.

My invention has for another of its objects the provision of means whereby signaling current may be withheld from desired lines that are previously busy and may be automatically applied to such lines when they have been restored to normal at their substations.

The above objects of my invention are specifically stated but the invention is not to be limited thereto as these objects and other objects and advantages will be appreciated by reference to the accompanying drawings, showing the preferred embodiment thereof, and in which—

Figures 1 and 2, taken collectively and in their numerical order with the conductors at the right and left hand sides thereof in alinement, illustrate a telephone exchange system equipped in accordance with the preferred embodiment of the invention.

I have shown two substations 200 and 201 whose lines, for the sake of simplicity in explaining the invention, are illustrated as extending to the same exchange. Each substation includes well known telephone equipment comprising a telephone switch hook 1, a call bell 2, a condenser 3, a telephone receiver 4, and a telephone transmitter 5, the telephone switch hook having a normal contact for including the bell and condenser in bridge of the associate telephone line when the receiver is upon the switch hook and having an alternate contact for including the receiver 4 and transmitter 5 in bridge of the associate telephone line when the switch hook is free of the telephone receiver. The limbs of the telephone lines terminate in waiting contacts 6 and 7, there being a plurality of each of these contacts for each line and which are multiply related, a pair of contacts 6, 7 being included in each of a number of switches that are employed for extending the telephone lines.

Each telephone line is shown with two pairs of contacts 6, 7 in connection with the wipers 8, 9 of such a switch and two other pairs of such contacts 6, 7 that are not shown with wipers 8, 9 resting in engagement therewith, the two upper pairs of waiting contacts being passed over by the wipers 8, 9 of the upper switch (Fig. 1) and the two lower pairs of these waiting

contacts being passed over by the wipers 8, 9 of the lower switch, these pairs of waiting contacts in each switch pertaining to different lines, it being understood that the 5 wipers 8, 9 of each switch pass over pairs of contacts 6, 7 pertaining to different lines, similarly positioned waiting contacts in the different switches being in multiple connection.

10 The wipers 8, 9 of each switch constitute terminals of link connectors and which terminals are operated to connect calling lines with the link connectors having such terminals. Thus each wiper 8 is connected 15 with one side 10 of a link connector and its companion 9 is connected with the other side 11 of such link connector. Each link connector side 10 has a waiting contact 12 complementary to the terminal 8 of such link connector side and each link connector side 11 has a waiting contact 13 complementary to the terminal 9 of such link connector side. The waiting contacts 12 and 13 of each link connector are in multiple connection, respectively, with similarly positioned contacts, these contacts 12 and 13 being distributed among a number of secondary selector switches having wipers 14 and 15, each pair of wipers 14, 15 passing over a number of 20 pairs of waiting contacts 12, 13 belonging to different link connectors. Each wiper 14 is connected with one side 16 of a link connector and its companion 15 is connected with the other side 17 of such link connector.

25 Each link connector side 16 has a wiper 18 complementary to the terminal 14 of such link connector side and each link connector side 17 has a wiper 19 complementary to the terminal 15 of such link connector side. Wipers 18 and 19 in each link connector 16, 17 constitute parts of a connector switch which is operated to bring these wipers into connection with the waiting contacts 6 and 7 that pertain to desired or called lines. A connection which is established between calling and called stations includes, by means of mechanism to be described, the calling line, its waiting contacts 6, 7, the wipers 8, 9 of a first or primary selector switch, the associate link connector 10, 11, the waiting contacts 12, 13 of this link connector, the wiping contacts 14, 15 of a secondary selector switch, the link connectors 16, 17 having these wiping contacts 14, 15, the wiping contacts 18, 19 of the link connectors 16, 17, and the waiting contacts 6, 7 of the desired line. The pairs of wipers 8, 9, 14, 15, 18 and 19 are preferably limited to single planes of rotation, these wipers being caused to travel by 30 associate ratchet wheels 20, 21 and 22 which in turn are respectively operated by motor magnets 23, 24 and 25 to bring the wipers into association with the proper waiting contacts to be employed for extending calling 35 and desired lines into connection.

Each link connector 10, 11 has a calling line selector switching device 8, 9, 20, 23 individual thereto and these link connectors and their associate selector switching devices are desirably divided into groups of, for example, ten to take care of the traffic for one hundred lines. This group of link connectors 10, 11 together with the group of calling line selector switches pertaining thereto is provided with a master switching device 75 common to such link connectors and their calling line selector switches, there thus being one such master switching device to each group of ten link connectors 10, 11. This master switching device includes wipers 26, 27, 28, 29 and 30 each common to its group of link connectors 10, 11 and these wipers are respectively provided with as many sets of waiting contacts 31, 32, 33, 34 and 35 as there are link connectors 10, 11, there thus 80 being, in the example chosen, ten of such waiting contacts 31, ten of 32, ten of 33, ten of 34, and ten of 35. The wipers 26 to 30 are desirably caused to move in single planes of rotation by means of a ratchet wheel 36 85 operated by a motor magnet 37, the relationship of the ratchet wheel 36 and motor magnet 37 being such that the wipers 26 to 30, when normal or idle, are in electrical connection with the waiting contacts 31 to 90 35 of some link connector 10, 11 in the group to which the wipers 26 to 30 pertain, these wipers stepping off the contacts with which they happen to be connected into connection with the succeeding set of waiting contacts 95 36 of some link connector 10, 11 having the first set of waiting contacts has become connected with the succeeding extension such as 16, 17, the wipers remaining in connection with these second named waiting contacts until another call is initiated whereupon these results are repeated.

Each master electro-magnetic switching mechanism 36, 37 has a setting up switching device individual thereto and which is employed for the purpose of establishing connection between the employed link connector 10, 11 and the succeeding link connector 16, 17. This setting up switching mechanism includes a pair of wipers 38, 39 caused to travel by a ratchet wheel 40 from a fixed position, to which fixed position these wipers are returned when they are no longer to perform their function in establishing a connection. The ratchet wheel 40 is operated 110 by a motor magnet 41 and is permitted to restore to normal by a restoring magnet 42 when this latter magnet is energized to attract the actuating pawl of the motor magnet 41 from engagement with the ratchet wheel. By means of apparatus to be described the wipers 38, 39 are brought into connection with waiting contacts 43 and 44 that are individual to a group of link connectors 16, 17, one of which is to be con- 115 120 125 130

connected with the link connector 10, 11 whereby the motor magnet 24 may be operated to bring the wipers 14, 15 of the desired link connector 16, 17 into engagement with the 5 waiting contacts 12, 13 of the link connector 10, 11 to be connected with the link connector 16, 17. The different pairs of waiting contacts 43, 44 are individual to different groups of link connectors 16, 17. Each link connector 16, 17 has a calling secondary selector switching device 14, 15, 21, 24 individual thereto and these link connectors and their associate secondary selector switching devices are desirably divided into groups of, 10 for example, ten. Each group of link connectors 16, 17 together with the group of second selector switches pertaining thereto is provided with a master switching device common to such link connectors and their 15 secondary selector switches 14, 15, 21 and 24, there thus being one such master switching device to each group of ten link connectors 16, 17. This master switching device includes wipers 45, 46, 47, 48, 49 and 50 each common to its group of link connectors 20 16, 17 and these wipers are respectively provided with as many sets of waiting contacts 51, 52, 53, 55 and 56 as there are link connectors 16, 17, there thus being, in the example chosen, ten such waiting contacts 51, 25 ten of 52, ten of 53, ten of 54, ten of 55 and ten of 56. The wipers 45—50 are desirably caused to move in single planes of rotation by means of a ratchet wheel 57 operated by 30 a motor magnet 58, the relationship of the ratchet wheel 57 and motor magnet 58 being such that the wipers 45—50, when normal or idle, are in electrical connection with the waiting contacts 51—56 of some link connector 16, 17 in the group to which the wipers 45—50 pertain, these wipers stepping off the contacts with which they happen to be connected into connection with the succeeding set of waiting contacts when the 35 link connector 16, 17 having the first set of waiting contacts has become connected with the succeeding extension such as the desired line, the wipers remaining in connection with these second named waiting contacts 40 until the new link 16, 17 has become connected with another desired or called line whereupon these results are repeated. Each master electro-magnetic switching mechanism 57, 58 has a setting up switching device 45 individual thereto and which is employed for the purpose of establishing connection between the employed link connector 16, 17 and a succeeding extension for the calling line, such for example as the desired or 50 called line. This setting up switching mechanism includes a wiper 59 caused to travel by a ratchet wheel 60 from a fixed position, to which position this wiper is returned when it is no longer to perform its function 55 in establishing a connection. The ratchet wheel 60 is operated by a motor magnet 61 and is permitted to restore to normal by a restoring magnet 62 when this latter magnet is energized to attract the actuating pawl of the motor magnet 61 from engagement 70 with the ratchet wheel. By means of apparatus to be described the wiper 59 is brought into connection with a waiting contact 63 that is individual to the line portion with which the link connector 16, 17 is to be connected, in this instance the called line, whereby the motor magnet 63 may be operated to bring the wipers 18, 19 of the employed link connector 16, 17 into engagement with the waiting contacts 6, 7 of the desired line. 75

The primary selector switch 20, 23 that happens to be electrically associated with the master switch 36, 37 is kept in constant operation until the wipers 8, 9, encounter the sides of a calling line, the circuit that causes such operation of this primary selector switch being traceable from the common grounded battery 64, the interrupter 65 that intermittently opens and closes this circuit, the switch spring 66 and its normal 90 contact, the left hand armature switch of the sluggishly operating relay 67 and its contact, the wiper 26, the waiting contact 31 that happens to be engaged by this wiper and individual to the motor magnet 23 that 95 is being operated, the winding of this motor magnet 23, the intermediate armature switch of the relay 68, to ground. When a subscriber initiates a call he first removes his telephone receiver from its switch hook, 100 thereby establishing a circuit, when the moving wipers 8, 9 encounter the waiting contacts 6, 7 of the calling subscriber's line, which circuit may be traced from the grounded battery 64, through the winding 105 of the sluggishly operating relay 67, the wiper 27, the waiting contact 32 then engaged by the wiper 27, the uppermost switch of the relay 68 and its normal follow-up contact, the wiper 8 which was in motion, the 110 waiting contact 6 of the calling line, both sides of the calling line, the waiting contact 7 of the calling line, the wiper 9 which was in motion, the lowermost armature switch of relay 68 and its normal follow-up contact, the wiper 28 and the waiting contact 33 then engaged thereby, the relay 69, to ground. The relay 67 is now energized, its left hand armature switch opening the circuit for the motor magnet 23, previously 115 traced, whereby the wipers 8, 9, that were moving are brought to rest in connection with the waiting contacts 6, 7 of the calling line. The relay 69 is now energized once, the armature switch of this relay closing a 120 circuit, once, for the motor magnet 41 to move the ratchet wheel 40 one step thereby to permit the spring 66 to leave its normal contact and engage its alternate contact, the separation of the switch 66 from its normal 125 130

contact occasioning a second gap in the circuit of the interrupter 65 for the sake of assurance, the wipers 38, 39 being at this time incidentally moved one step without 5 engaging any waiting contacts 43, 44. The lines are normally free of battery, a calling line having battery initially placed thereupon when the relay 67 is energized in the manner described whereby a click is manifested in the receiver 4 of the calling subscriber serving to notify the calling subscriber that he may proceed with his call. The calling subscriber thereupon operates any suitable or well known circuit interrupting mechanism, such as a dial mechanism, this circuit interrupting mechanism being diagrammatically illustrated at 70. The device 70 is manipulated the number of times which is required to bring the wipers 38, 20 39 into engagement with that pair of waiting contacts 43, 44, individual to a link connector 16, 17 that is provided with a connector switch 25 having waiting contacts 6, 7 which pertain to the desired line. It is 25 understood that the link connectors 16, 17 may extend to different exchanges and are to be selected by the calling subscriber accordingly or they may extend to different groups of telephone lines in the same exchange. From a circuit previously traced 30 this result is accomplished by opening and closing the circuit of the relay 69 by the switch 70 the predetermined number of times to bring the wipers 38, 39 into engagement with the proper waiting contacts 43, 44. The circuit governed by the relay 69 may be traced from the grounded common battery 64, the armature switch of relay 69, to the grounded motor magnet 41. When 35 the wipers 38, 39 have been engaged with their proper waiting contacts 43, 44 they, of course, remain in engagement with such contacts during the establishment of the connection of the desired link connector 16, 17 with the link connector 10, 11, the wipers 38, 39 in passing over other waiting contacts 43, 44 not having opportunity to make any effective circuit changes. When the wipers 38, 39 have thus been arrested during the 40 cessation of the operation of the switch 70 in engagement with the desired waiting contacts 43, 44, a circuit is established which is traceable from the grounded battery 64, through the interrupter 65, the switch 66 and its then engaged alternate contact, the wiper 39, the waiting contact 44 then engaged thereby, the left hand armature switch of relay 71 and its then engaged contact, the setting up switch wiper 45, the 45 waiting contact 51 engaged by this wiper, the motor magnet 24 of the secondary selector switch, the intermediate armature switch of the relay 72 and its left hand follow-up contact, to ground. 50 The motor magnet 24 is thus operated un- til its wipers 14, 16 engage the waiting contacts 12, 13 of the link 10, 11 now connected with the calling line whereupon a circuit is established for the relay 68 which is traceable from the battery 73, through the right 55 hand armature switch of relay 67 and its alternate contact, the wiper 29, the waiting contact 34 that is engaged by this wiper, the lower winding of relay 68, the waiting contact 13, the wiper 15 of the employed secondary selector switch 21, 24, the lowermost armature switch of relay 72 and its normal follow-up contact, the waiting contact 53 individual to the employed link-connector 16, 17, the wiper 47 engaging the waiting contact 53, the left hand winding of relay 71, the second armature switch from the left belonging to the relay 71 and the follow-up contact of this armature switch, the waiting contact 43 individual to the employed link connector 16, 17, the wiper 38 now engaging this waiting contact 43, the now released switch 74 and its now engaged contact, the winding of the release magnet 42, back to the battery 73. The relay 71 is thus energized and the left hand armature switch of this relay opens the circuit of the employed motor magnet 24 to keep the wipers 14, 15 individual thereto in connection with the 60 waiting contacts 12, 13 of the link connector 10, 11 that is connected with the calling subscriber. The release magnet 42 was included in the circuit just traced so that the ratchet wheel 40 is restored to normal permitting this ratchet wheel and the setting up switch 65 of which it formed a part to be employed in setting up a new connection when initiated, the circuit of the motor magnet 41 being now open owing to the shifting of the wipers 26—30 to their engagement with waiting 70 contacts 31—35 of a succeeding set of waiting contacts pertaining to an idle link connector 10, 11 by a circuit traceable from the grounded battery 64, the motor magnet 37, the wiper 30, the waiting contact 35 first engaged by the wiper 30, the intermediate armature switch of relay 68 and its alternate contact, to ground, the motor magnet 37 operating one step if the next succeeding set of waiting contacts 31, 35 pertain to an idle 75 link connector is idle, but if such succeeding set of waiting contacts pertains to a busy link connector the intermediate armature switch of the relay 68 of such next busy link connector is in engagement with its alternate contact so that the motor magnet 37 is again energized, the wipers 26—30 thus continuing in movement until they engage idle waiting contacts. The opening of the motor magnet 41 occurs at the armature switch of relay 69 80 when thus deenergized. The relay 67 is sluggishly operating so that the relay 69 may be rapidly operated in responding to the movements of the switch 70 while the armature switches of the relay 67 remain in 85 90 95 100 105 110 115 120 125 130

their attracted positions. If the calling subscriber should change his mind and not desire to extend his telephone line into connection with another line and not having operated his dial 70, such subscriber will merely restore his receiver upon its switch hook whereupon circuit will be established through the release magnet 42 to restore the wipers 38, 39 to their normal or zero position, such release magnet circuit being traceable from the battery 72, the right hand armature switch of relay 67 and its normal contact, the switch 74 and its then engaged contact, the release magnet 42, back to the battery 73. A locking circuit is established for the relay 68 which is traceable from the grounded battery 64, the upper winding of the relay 68, the left hand alternate contact of the uppermost armature switch of relay 68, this uppermost armature switch, the right hand alternate contact of this armature switch, the waiting contact 12, the wiper 14 now engaging the contact 12, the uppermost armature switch of relay 72 and its normal follow-up contact, the waiting contact 52, the wiper 46, the armature switch immediately to the right of the windings of the sluggishly operating relay 71 and the contact now engaged by this armature switch, the right hand winding of relay 71, the left hand armature switch of relay 73, to ground, the relay 73 having been energized by a circuit (which is also a holding circuit for relay 74) traceable from the grounded terminal thereof through the winding of the relay 75, the second armature switch to the right of the windings of relay 71, the contact then engaged by this armature switch, the wiper 47, the waiting contact 53 then engaged by the wiper 47, the lowermost armature switch of relay 72 and its normal follow-up contact, a portion of the link conductor 17, the wiper 15, the waiting contact 13 now engaged by the wiper 15, the lowermost armature switch of relay 68 and its alternate contact, the employed wiper 9, the waiting contact 7 of the calling line engaged by the wiper 9, both sides of the calling line, the waiting contact 6 of the calling line, the wiper 8 engaging said waiting contact 6, the uppermost armature switch of relay 68 and its left hand alternate contact, the upper winding of relay 68, to the grounded battery 64.

55 The calling subscriber will continue the operation of the switch 70 to bring the wipers 18, 19 of the employed link connector 16, 17 into connection with the waiting contacts 6, 7 of the desired line. The switch 70 will now be operated to interrupt the circuit of the motor magnet 61 the number of times predetermined by the calling subscriber to bring the wiper 59 into engagement with the waiting contact 63 of the desired line, the switch 70 operating directly to open and close the circuit of the relay 75, while the right hand armature switch of the relay 75 operates directly to open and close the circuit of the motor magnet 61 for the purpose stated. When the wiper 59 has been brought into engagement with the selected waiting contact 63 a circuit is established for the motor magnet 25 which includes the grounded battery 64, the interrupter 65, the switch spring 76 and the contact engaged thereby when the ratchet wheel 60 has been moved the first step from normal, the wiper 50, the waiting contact 56, the winding of the motor magnet 25, and the intermediate grounded armature switch of the relay 72 and its right hand normal follow-up contact. The motor magnet 25 will thus be operated until its wipers 18, 19 are brought into connection with the waiting contact 6, 7 that pertains to the same line with which the engaged waiting contact 63 pertains. When the wipers 18, 19 are engaged with such waiting contacts 6, 7, a circuit is closed that is traceable from the battery 77, through the extreme right hand armature switch of sluggishly operating relay 71 and its alternate contact, the wiper 48, the waiting contact 54, the lower winding of the relay 72, the right hand armature switch of relay 78 and its normal contact, the lower armature switch of relay 79 and its normal follow-up contact, the wiper 19, the waiting contact 7 engaged thereby, the waiting contact 63, the wiper 59 engaged thereby, the switch spring 80 and the contact which was engaged thereby when the ratchet wheel 60 moved its first step from normal, the winding of release magnet 62, back to the battery 77. The release magnet 62 will withdraw the actuating pawl operated by the motor magnet 61 whereupon the wiper 59 will be restored to normal, and when this wiper 59 reaches normal the switch springs 76 and 80 are removed from engagement with their contacts whereupon the circuit of the motor magnet 25 is opened and the wipers 18, 19 are caused to remain at rest with the waiting contacts 6, 7 of the desired line. A holding circuit is established for the energized relay 72 that is traceable from the grounded battery 64, the upper winding of this relay, the upper armature switch of the relay and its alternate contact, the wiper 14, the waiting contact 12, the right hand alternate contact of the uppermost armature switch of the relay 68, this armature switch, the wipers 8, 9, the waiting contacts 6, 7, engaged by these wipers, and the calling line having the waiting contacts 6, 7, the lowermost armature switch of the relay 68 and its alternate contact, the waiting contact 13, the wiper 15, the lowermost armature switch of relay 72 and its alternate contact, the left hand winding of relay 78 (the holding circuit for the 100

105 110 115 120 125 130

relay 72 also constituting a holding circuit for the relay 78) the right hand alternate contact of the intermediate armature switch of relay 72, said armature switch, to ground. Circuit is established for the motor magnet 58 traceable from the grounded battery 64, the winding of this motor magnet, the wiper 49, the waiting contact 55, the left hand alternate contact of the intermediate armature switch of relay 72 to ground whereby the motor magnet 58 is operated to move the wipers 45 to 50 from the waiting contacts 51-56 with which they were in engagement and into engagement with another set of waiting contacts 51-56 that pertain to an unemployed link connector 16, 17.

If the line wanted is busy circuit is established for the relay 81 which is traceable from the grounded battery 64, the left hand armature switch of relay 78 and its contact, the winding of relay 81, the uppermost armature switch of relay 79 and its normal contact, the wiper 18, the waiting contact 6 engaged thereby, another waiting contact 6 connected with the wanted line and there engaged either by another wiper 18 or another wiper 8 accordingly as the wanted line is a previously called line or a previously calling line, through both sides of the wanted previously busy line, the waiting contact 7 complementary to the second waiting contact 6, thence to the grounded intermediate armature switch of the relay 72 by way of one or the other of the windings 78 as will be apparent. The relay 81 being thus energized opens the circuit for the ringing current generator 82 so that current from this generator cannot find passage to the wanted previously busy line until the relay 81 is deenergized, an occurrence which arises when the telephone receiver at the wanted station is restored to its switch hook whereupon the bell at this wanted station is rung and the party there again responds, the signaling current finding passage from the grounded generator 82, the lower winding of the ringing relay 79, the armature switch of the now deenergized relay 81 and its then engaged contact, the alternate contact of the right hand armature switch of relay 78, this armature switch, the lowermost armature switch of relay 79 and its normal follow-up contact, the wiper 19, the waiting contact 7, both sides of the wanted line, the bell bridge at the substation of the wanted line, the waiting contact 6, the wiper 18, the uppermost armature switch of the relay 79 and its normal contact, this armature switch and normal contact serving to shunt the upper winding of the relay 79, the winding of relay 81, the left hand armature switch of relay 78 and its engaged contact, to the grounded battery 64. The relays 79 and 81 are of such resistance that they will not be effectively energized by the current passing through the same and the signal bell at the called station, but when the low resistance bridge including the receiver and transmitter at the called station is substituted for the comparatively high resistance signal bell bridge thereat current from the generator 82 is sufficiently increased to energize the relay 79, the circuit for the relay 81 being then open at the normal contact of the upper armature switch of the relay 79. When the relay 79 is thus energized another holding circuit is established for the relay 78 which is traceable from the grounded battery 64 through the left hand armature switch of relay 78 and its contact, the winding of relay 81, the upper winding of relay 79, the wipers 18, 19 and the contacts 6, 7 of the called line, both sides of the called line now connected through the telephone receiver and transmitter at the called substation thereof, the lower armature switch of relay 79 and its alternate contact, the right hand winding of relay 78, the right hand alternate contact of the intermediate armature switch of the relay 72, this armature switch, to ground. The circuit thus traced also constitutes a holding circuit for the relays 79 and 81, the relay 81 now operating to remove the generator 82 from circuit with the wanted line. The armature switches 79, by engaging their alternate contacts, telephonically complete the normally separated sections of the link conductors 16, 17. Current is supplied to the transmitters at the connected stations by a path a section of which is traceable from the grounded battery 64, through the upper winding of the relay 72, the uppermost armature switch of this relay and its normal contact, to the link conductor 16 and the other section of which is traceable from the companion link conductor 17, the lowermost armature switch of relay 72, the alternate contact of this switch, the left hand winding of relay 78, the right hand alternate contact of the intermediate armature switch of relay 72, this intermediate armature switch, to ground, current from battery 64 thus finding passage in both directions through the upper winding of relay 72 so that this relay will remain energized until both subscribers have restored their receivers upon their switch hooks.

It will be observed that the wipers of the electro-magnetic connector switching devices at 20, 21 and 22 are always in engagement with some waiting contacts, when such wipers are at rest, whether the wipers are in or out of circuit, the system of my invention avoiding the necessity of restoring mechanism for the switches.

It will be observed that each of the link connectors includes but two conductors

which are talking sides by means of which the necessary switching functions are performed, no third conductor being required in any of the link connectors for this purpose. It will also be observed that the second link connectors (16, 17) seek the first link connectors instead of being sought by the first link connectors. It will also be observed that the relays 68 and 72 normally operate to separate the link connectors with which they are associated each into two telephonically distinct sections, these relays being energized by the calling subscriber, at the proper time, telephonically to complete their associate link connectors whereby all wiper contacts 8, 9, 14, 15, and 18, 19, may remain in connection with the waiting contacts with which they were brought into engagement whereby stepping up mechanism 20 and release mechanism individual to the different link connectors are dispensed with.

While I have herein shown and particularly described the preferred embodiment of my invention I do not wish to be limited to the precise construction and circuit arrangement shown as changes may readily be made without departing from the spirit of my invention, nor do I wish to be limited, in all embodiments of the invention, to a system in which the calling subscribers are adapted to effect connection of their lines with called lines without the aid of operators.

Having thus described my invention I claim as new and desire to secure by Letters Patent the following:

1. A telephone exchange system including telephone lines extending from substations to an exchange; a group of link connectors for effecting connection between telephone lines; electro-magnetic connector switching devices for extending said link connectors that have become connected with calling lines and individual to the link connectors of said group; a calling subscriber controlled master switching device common to and interchangeably associated with the link connectors of said group and taking part in the control of the operation of said connector switching devices; and setting up switching mechanism for selecting the connector switching devices which are to be operated.

2. A telephone exchange system including telephone lines extending from substations to an exchange; a group of link connectors for effecting connection between telephone lines; calling subscriber controlled electro-magnetic connector switching devices for extending said link connectors that have become connected with calling lines and individual to the link connectors of said group; a master switching device common to and interchangeably associated with the link connectors of said group and taking part in the control of the operation of said connec-

tor switching devices; and setting up switching mechanism for selecting the connector switching devices which are to be operated.

3. A telephone exchange system including telephone lines extending from substations to an exchange; a group of link connectors for effecting connection between telephone lines; calling subscriber controlled electro-magnetic connector switching devices for extending said link connectors that have become connected with calling lines and individual to the link connectors of said group; a calling subscriber controlled master switching device common to and interchangeably associated with the link connectors of said group and taking part in the control of the operation of said connector switching devices; and setting up switching mechanism for selecting the connector switching devices which are to be operated.

4. A telephone exchange system including telephone lines extending from substations to an exchange; a group of link connectors for effecting connection between telephone lines; electro-magnetic connector switching devices for extending said link connectors that have become connected with calling lines and individual to the link connectors of said group; a master switching device common to and interchangeably associated with the link connectors of said group and taking part in the control of the operation of said connector switching devices; and calling subscriber controlled setting up switching mechanism for selecting the connector switching devices which are to be operated.

5. A telephone exchange system including telephone lines extending from substations to an exchange; a group of link connectors for effecting connection between telephone lines; electro-magnetic connector switching devices for extending said link connectors that have become connected with calling lines and individual to the link connectors of said group; a calling subscriber controlled master switching device common to and interchangeably associated with the link connectors of said group and taking part in the control of the operation of said connector switching devices; and calling subscriber controlled setting up switching mechanism for selecting the connector switching devices which are to be operated.

6. A telephone exchange system including telephone lines extending from substations to an exchange; a group of link connectors for effecting connection between telephone lines; calling subscriber controlled electro-magnetic connector switching devices for extending said link connectors that have become connected with calling lines and individual to the link connectors of said group; a master switching device common to and interchangeably associated with the link con-

nectors of said group and taking part in the control of the operation of said connector switching devices; and calling subscriber controlled setting up switching mechanism for selecting the connector switching devices which are to be operated.

7. A telephone exchange system including telephone lines extending from substations to an exchange; a group of link connectors for effecting connection between telephone lines; calling subscriber controlled electro-magnetic connector switching devices for extending said link connectors that have become connected with calling lines and individual to the link connectors of said group; a calling subscriber controlled master switching device common to and interchangeably associated with the link connectors of said group and taking part in the control of the operation of said connector switching devices; and calling subscriber controlled setting up switching mechanism for selecting the connector switching devices which are to be operated.

25 8. A telephone exchange system including telephone lines extending from substations to an exchange; means for applying signaling current to desired lines; electro-magnetic means governed by desired lines for withholding the application of signaling current thereto when said desired lines are previously busy and for effecting the application of signaling current to such lines when restored to normal at their substations; link connectors for joining telephone lines in conversation; switching mechanism for normally dividing the same into sections; and additional electro-magnetic means operated by signaling current when flowing to desired lines whose stations have responded for operating said switching mechanism telephonically to join said sections.

9. A telephone exchange system including a group of telephone conductor sections; electro-magnetic connector switching devices for extending said telephone conductor sections; electro-magnetic setting up switching mechanism at the exchange and common to the electro-magnetic connector switching devices for selecting the connector switching devices which are to be operated; means at the stations of the lines which are operable at calling stations for actuating the setting up switching mechanism; and a calling subscriber controlled master switching device common to and interchangeably associated with the telephone conductor sections of said group and through which master switching device the setting up switching mechanism 60 operates.

10. A telephone exchange system including telephone lines extending from substations to an exchange; electro-magnetic connector switching devices for extending the

telephone lines and including wipers and 65 waiting contacts, the wipers whether in or out of circuit, engaging waiting contacts when such wipers are at rest; electro-magnetic setting up switching mechanism at the exchange and common to said electro-magnetic 70 connector switching devices for determining the line extension to be added to a calling line; means at the stations of the lines which are operable at calling stations for actuating the setting up switching mechanism; and a calling subscriber controlled master switching device common to and interchangeably associated with the telephone conductor sections of said group and through which master switching device the 80 setting up switching mechanism operates.

11. A telephone exchange system including telephone lines extending to an exchange; successive sets of conductor sections; electro-magnetic connector switching 85 devices pertaining to the conductor sections of different sets for extending said telephone conductor sections; a master switch for each set of telephone conductor sections and common to the electro-magnetic connector switching devices pertaining thereto and provided with means for selecting an idle electro-magnetic switching device to adapt it to its function; a setting up switch common to the electro-magnetic switching devices pertaining to each set of telephone conductor sections; subscriber controlled means at the stations of the telephone lines and operated at calling stations for operating the setting up switches; means 90 whereby a setting up switch may select a succeeding selector switch; and means whereby this latter setting up switch may coöperate with the selector switch it has selected to operate the electro-magnetic 95 switching device coupled with this selected selector switch.

12. A telephone exchange system including telephone lines extending to an exchange; a plurality of sets of telephone 110 conductor sections; electro-magnetic connector switching devices pertaining to the conductor sections of different sets for extending said telephone conductor sections; a master switch for each set of electro-magnetic connector switching devices and provided with means for effecting its association with an unemployed electro-magnetic connector switching device in the set to which it pertains; a setting up switch in 115 interchangeable relation with the master switches and provided with means for bringing it into association with an unemployed master switch to bring the setting up switch into association with the electro-magnetic connector switching device coupled with such unemployed master switch; and subscriber controlled means at the stations 120 125

of the telephone lines and operated at calling stations for operating the setting up switch.

13. A telephone exchange system including telephone lines extending to an exchange; a plurality of sets of line extending electro-magnetic connector switching devices; a master switch for each set of electro-magnetic connector switching devices and provided with means for effecting its association with an unemployed electro-magnetic connector switching device in the set to which it pertains; a setting up switch in interchangeable relation with the master switches and provided with means for bringing it into association with an unemployed master switch to bring the setting up switch into association with the electro-magnetic connector switching device coupled with such unemployed master switch; and subscriber controlled means at the stations of the telephone lines and operated at calling stations for operating the setting up switch.

14. A telephone exchange system including telephone lines extending to an exchange; electro-magnetic line extending connector switching devices; a master switch provided with means for effecting its association with an unemployed electro-magnetic connector switching device; a setting up switch operatively associated by the master switch with the electro-magnetic connector switching device coupled with such master switch; and subscriber controlled means at the stations of the telephone lines and operated at calling stations for operating the setting up switch.

15. A telephone exchange system includ-

ing telephone lines extending to an exchange; link connectors; calling subscriber controlled switching mechanism for connecting link connectors with calling lines; succeeding link connectors; and means for connecting a succeeding link connector with a preceding link connector and operating to place a free one of the first mentioned link connectors in condition to be connected with another calling line.

16. A telephone exchange system including telephone lines extending to an exchange; link connectors; calling subscriber controlled switching mechanism for connecting link connectors with calling lines; succeeding link connectors; and subscriber controlled means for connecting a succeeding link connector with a preceding link connector and operating to place a free one of the first mentioned link connectors in condition to be connected with another calling line.

17. A telephone exchange system including telephone lines extending to an exchange; electro-magnetic line extending connector switching devices; a setting up switch; means for effecting the association of the setting up switch with an unemployed electro-magnetic line extending connector switching device; and means for operating the setting up switch.

In witness whereof, I hereunto subscribe my name this thirty-first day of March, A. D. 1913.

ELMER R. CORWIN.
